UNITED STATES PATENT OFFICE

FREDERICK M. BRAEGER, OF ERIE, PENNSYLVANIA

SKYLIGHT

Application filed February 21, 1928. Serial No. 255,920.

This invention is designed to improve sky lights, particularly as to the truss bars and wall construction of the sky light. Features and details of the invention will appear from the specification and claims.

A preferred embodiment of the invention is illustrated in the accompanying drawings as follows:

Fig. 1 shows a perspective view of the sky light.

Fig. 2 a section on the line 2—2 in Fig. 1.

Fig. 3 a section on the line 3—3 in Fig. 4.

Fig. 4 a section on the line 4—4 in Fig. 3.

Fig. 5 a section on the line 5—5 in Fig. 1.

15 1 marks the sky light box, 2 side plates resting on the ends of the side walls, a plate 3 along the upper side and a plate 4 along the lower side. The plate 3 is secured to the box preferably of wood and its upper edge has a 20 fold 5 terminating in a gutter 6, the inner edge of the gutter being folded at 7 to form a glass support. A cap piece 7^a is arranged over the top edge of the glass. A re-enforcing and supporting plate 8 is secured on the 25 inner face of the wall 3, the upper edge extending into the fold 5. This has an inwardly extending flange 9 terminating in a gutter 10. The flange 9 rests on the top of the box 1.

30 The side plate 4 has an inward fold 11 forming a flange resting on the top of the side box. Truss bars 12 are formed of sheet metal of prismatic shape of triangular section, the top having supporting surfaces 13 between which is formed a trough 14. The sides of the bar 15 are brought together at 16 and have outwardly extending flanges 17 terminating in an upturned bend 18. The bottom edges are locked together by a tie 40 plate 19 which has folds 20 extending over the edges 18, the upturned edges forming a gutter which will receive and carry out any condensation that may reach the truss bar. Glass 21 rests on packing strips 22, preferably of asbestos which form cushions for the edges of the glass and also tend to close the joint between the glass and the bar.

45 A cap 23 extends lengthwise of the joint formed between the edges of the glass. A bolt 24 has its head 25 secured within a bridge

piece 26 secured in the gutter 14. A nut 25^a arranged on the top of the cap secures the cap in place. A truss rod 27 is arranged within the bar 12. It extends around a strut 28 at the center and through the side walls 3 and 4 and through longitudinally extending band strips 29 along the outer faces of the side walls, the ends of the rods being provided with nuts 30. The strut 28 is formed of a 55 triangular plate with side flanges 31 which are secured to the walls 15 by screws 32.

The upper edge of the side plate 4 has a flange 4^a terminating in an inturned hook 4^b. A bottom strip 33 extends along the bottom edge of the glass. This strip hooks over the bottom of the glass and the edge of the bottom of this hook strip has an out-turned bend 34 which hooks into the hook, or return bend 4^b, thus locking the strip 33 with the side plate 4. The gutter walls of the bar 12 extend through the side wall 3 thus carrying any leakage through the joint between the edges of the glass out through the side walls. At the extreme ends of the sky light a half 70 bar 35 similar to the bar 12 is used in connection with the wall, or plate 2 and in this bar no truss rod is used and the cap at the top is only a half cap 36. Otherwise the structure is similar to the bar 12 and the cap 23.

75 What I claim as new is:

1. In a sky light, the combination of a truss bar comprising a sheet metal structure of prismatic shape and triangular cross section with a horizontal side at the top; a truss rod within the bar; and side walls abutting the ends of the bar.

2. In a sky light, the combination of a truss bar comprising a sheet metal structure of prismatic shape and triangular cross section with a horizontal side at the top; side walls abutting the ends of the bar; and a truss rod within the bar extending through the side walls.

3. In a sky light, the combination of a truss bar comprising a sheet metal structure of prismatic shape and triangular cross section with a horizontal side at the top; side walls abutting the ends of the bar; a truss rod within the bar extending through the side walls; and band strips along the outer

faces of the side walls to which the truss rod is secured.

4. In a sky light, the combination of a truss bar comprising a sheet metal structure of prismatic shape and triangular cross section with a horizontal side at the top; a truss rod within the bar; and a strut for the rod secured to the side walls of the bar.

5. In a sky light, the combination of a truss bar comprising a sheet metal structure of prismatic shape and triangular cross section with a horizontal side at the top, said top having glass supporting faces at each side and an intervening gutter; and a truss rod arranged within the bar.

6. In a sky light, the combination of a truss bar comprising a sheet metal structure of prismatic shape formed with a horizontal side at the top; side walls joined at the bottom; flanges extending from the bottom of the side walls forming gutters; means for securing the bottoms of the side walls together; a truss rod arranged within the bar, said truss rod having its ends secured to the top of the bar and its intermediate portion adjacent to the bottom of the bar; and a strut connecting the part of the rod adjacent to the bottom of the bar and the top of the bar, said strut and rod being housed within the bar.

7. In a sky light, the combination of a truss bar comprising a sheet metal structure of prismatic shape and triangular cross section with a horizontal side at the top, said top having glass supporting faces at each side and an intervening gutter; a truss rod arranged within the bar; and side walls abutting the ends of the truss bar, the gutter of the truss bar extending through the lower side wall.

8. In a sky light, the combination of a truss bar comprising a sheet metal structure of prismatic shape and triangular cross section with a horizontal side at the top, said top having glass supporting faces at each side and an intervening gutter; a truss rod arranged within the bar; glass arranged on the glass supports; a cap over the gutter and resting on the glass; and means extending from the truss bar securing the cap.

9. In a sky light, the combination of a truss bar comprising a sheet metal structure of prismatic shape and triangular cross section with a horizontal side at the top, said top having glass supporting faces at each side and an intervening gutter; a truss rod arranged within the bar; glass arranged on the glass supports; a cap over the gutter and resting on the glass; and means extending from the truss bar securing the cap comprising bolts extending between the edges of the glass and bridge pieces secured in the gutter walls to which said bolts are secured.

10. In a sky light, the combination of truss bars; glass supported on the truss bars; a side plate abutting the truss bars along their

lower edges and arranged beneath the glass, said side plate having an outwardly extending flange with a hooked edge; and an edge plate extending along the bottom edges of the glass having an inturned portion below the glass with a hooked edge engaging the hooked edge of the side plate.

11. In a sky light, the combination of truss bars; and a side plate having an inwardly turned loop forming a box support abutting the ends of the truss bars.

In testimony whereof I have hereunto set my hand.

FREDERICK M. BRAEGER.
